UNITED STATES PATENT OFFICE.

TENGEL ANDERSEN, OF PORT RICHMOND, NEW YORK.

GUIDE FOR POWER HAMMERS.

Application filed March 6, 1922. Serial No. 541,462.

To all whom it may concern:

Be it known that I, TENGEL ANDERSEN, a citizen of the United States, residing at 14 Grove Place, Port Richmond, county of Richmond, and State of New York, have invented certain new and useful Improvements in Guides for Power Hammers, fully described and represented in the following specification and the accompanying drawings, forming a part of the same.

This invention relates to a lead or guide for a movable body and relates more particularly to a guide for confirming the movement of a suspended power hammer in a rectilinear path.

Power hammers have proven of great value for driving piling and when employed for this purpose are usually suspended by means of a cable from the end of a boom.

20 The hammer is then carried by the boom to an operative position with respect to a pile, whereupon the pile and hammer are so juxtaposed that an actuation of the hammer effects a succession of blows upon the pile with the result that the pile is driven into the ground.

As the pile moves downwardly the hammer must necessarily follow, the downward movement of the hammer being permitted 30 by the manipulation of the drum upon which the cable, supporting the hammer, is wound.

Steam or pneumatic hammers for pile driving purposes are cumbersome bodies and 35 essentially of great weight. It therefore becomes necessary to provide a guide or lead which will confine the vertical movement of the hammer to a given path and thus facilitate its guidance throughout its movement 40 between the boom and the ground or body into which a pile is to be driven.

An object of the present invention is to provide a guide which may be so associated 45 with a hammer as to maintain its movement substantially unidirectionally throughout its length of travel. Another object of the invention is to provide a guide so constituted that it may be readily adjusted to control the movement 50 of the hammer when the distance of travel of the said hammer is varied.

Other objects and advantages will be ap-

parent upon a reading of the following specification and by reference to the accompanying drawings in which—

55 Fig. 1 shows my guide as applied to a steam hammer.

Fig. 2 is an elevational view of the guide partly in section.

Fig. 3 is another elevational view partly 60 in section.

Fig. 4 is a view taken on line IV—IV in Fig. 2.

Fig. 5 is a side view of one of the yokes for connecting the guide member with the hammer and Fig. 6 is a section taken on line VI—VI in Fig. 5.

70 My improved lead or guide may comprise a plurality of sections capable of relative movement to produce a variation in the length of the guide. These sections are preferably of tubular form and concentrically disposed and adapted to be collapsed or expanded at will. The guide is provided at its upper end with means for detachably connecting it to the end of a boom and at its lower end with a suitable tip or nose piece to facilitate its insertion into the ground or other body.

75 Referring now to the drawing the embodiment of my invention shown may consist of a guide comprising two sections or members 10 and 11. The inside diameter of the member 10 is of such dimension as to provide a sliding fit for the section 11 which is inserted therein. It will thus be seen that the sections are relatively movable and a guide so constituted may be lengthened or shortened by collapsing or nesting the two sections.

80 The normal upper end of the section 10 is provided with a yoke or shackle 12 pivoted on a bolt 13 which extends transversely through the section 10. Positioned within the yoke is a sheave 14 mounted on a shaft 85 15 which has its bearing in the sides of the yoke.

85 The sheave 14 is provided to guide a cable 16 which is led thereover and connected to a link 17 secured in an eye 18 of a cap 19 which is tightly fitted within and riveted or otherwise secured to the upper end of the tubular member 11.

100 It is obvious that the member 11 when in proper position will be held firmly in

its upper position, will move downwardly by virtue of its potential energy and such downward movement may be limited by sufficient opposing force as may result from a 5 pull upon the cable 16. Thus the cable will serve to move the member 11 upwardly within the member 10 and a release or play upon the cable will allow the member 11 to drop to any relative position depending 10 on the length of cable played out.

Although the member 11 may be limited in its movement by a manipulation of the cable 16 it is desirable to provide an additional fixed stop to prevent the accidental 15 disengagement of the two members 10 and 11. I provide a stop for this purpose which comprises a rod 20 axially disposed within the member 10 and secured to the bolt 13 at the upper end thereof. This rod extends 20 through the cap 19 which is movable longitudinally thereof. Thus the member 11 may move longitudinally of the rod which is provided with a nut 21 at its lower end to arrest the downward movement of the member 11. 25 For the purpose of dissipating vibration due to an impact of the cap 19 upon the nut 21 I provide a resilient member such as the helical spring 22 disposed about the rod and between the cap 19 and the nut 21. It will 30 therefore be evident that when the member 11 is permitted to fall to the limit of its downward movement the shock or jar which would otherwise be transmitted throughout the member and possibly disturb the position 35 of the boom, will be appreciably absorbed by the resilient member and any shearing force that would otherwise be exerted upon the rivets or bolts, which secure the cap 19 to the member 11 is avoided.

40 It will be understood that when the member 11 is in its lowermost position a sufficient portion of its length remains within the member 10 to maintain a substantially uniform strength throughout the length of the 45 guide against lateral thrust.

At the lower end of the member 11 I provide a plug or nose piece 23 which may be either permanently fastened to the member as by riveting or may be removably secured 50 thereto as shown in Fig. 2. The means for holding the movable plug 23 in detachable association with the member 11 comprises a sleeve 24 diametrically disposed within the plug and in which are positioned two movable pins 25 and 26 normally urged toward the ends of the sleeve through the expansion action of a spring 27 which is disposed 55 between the inner ends of the pins. The outer ends of the pins are of relatively small 60 diameter for a given portion of their length and shoulders 28 and 29 are thus produced and the plug 23 is secured in the end of the member 11 by the disposition of the reduced ends of the pins 65 in diametrically oppositely positioned aper-

tures in the member 11. The plug 23 is also provided with a shoulder 30 against which the member 11 contacts. I also provide the plug 23 with an eye 31 for the convenient attachment of cable by means of 70 which the end of the guide may be moved from its vertical position and so maintained for the purpose of driving a pile at an angle.

Where desirable I may employ an extension piece 32 which is preferably secured to 75 the lower end of the member 11 by means of pins 25 and 26 by the same means as is employed for securing the nose piece 23 to the member 11 as above described.

For the purpose of associating my guide 80 with a power hammer I provide one or more yokes or guide rings 33. These rings are provided with projections 34 having bolt holes 35 therein, whereby the rings may be secured to the hammer by tap bolts 36. The 85 rings are preferably constructed of a strip of metal which, in transverse cross section, is of dish shape with its convex surface adjacent the guide when the guide rings are positioned therearound. The peculiar shape of 90 this ring permits its movement with the hammer longitudinally of the guide, it being evident that the rounded surfaces 37 will ride freely over any irregularities upon the surface of the guide, as for instance the 95 lower end of the member 10.

In practice my guide is secured to the end 100 of any suitable carrier usually a boom 38 (shown in dotted lines) which may be mounted on either a barge, vehicle or upon the ground. The usual tackle may be provided for elevating a power hammer 40 which may comprise a reciprocable member carried in the usual casing. My guide may be secured to the upper end of the boom by a coupling 41. The guide rings 33 may then be disposed about the guide and fastened to the hammer. The vertical movement of the hammer will thereby be maintained throughout its entire travel and the hammer 40 may be raised to a sufficient height and a pile 42 positioned beneath the hammer in position to be driven into the earth. As the pile moves downwardly the hammer follows in a given path by virtue of its association with the guide.

110 It will be appreciated that when the distance between the end of the boom and the ground is varied the guide may be adjusted to increase or decrease its length, or if the earth in which the lower end of the guide is embedded is of relatively soft material the guide may enter to such a depth as may be necessary in which cases the guide may be readily adjusted and maintained in such 115 position.

120 My invention therefore provides a convenient and useful means for guiding the movement of an automatic hammer and it is obvious that it may be used in all cases 125 130

where a hammer or other weighty body requires a guide between its point of suspension and the lower limit of its movement.

Although I have shown a preferred embodiment of my invention it is evident that many modifications may be made therein as for instance the guide may consist of a multiplicity of short sections which may be collapsed, and it is to be understood that such and other modifications are to be considered within the spirit and scope of the appended claims.

What is claimed is—

1. A guide for power hammers comprising a plurality of concentrically positioned and adjustable members adapted to be held in different relative positions to vary the length of the guide.
2. A guide for a power hammer comprising a plurality of rigid members adapted for relative adjustment to vary the length of said guide, and means for limiting the relative movement of said members.
3. An attachment for a power hammer comprising a guide, means for associating said guide with said hammer, said guide having a plurality of nested tubular members, means for slidably attaching said guide

to said hammer and means for limiting the relative movement of said members. 30

4. An attachment for a power hammer comprising a guide including a plurality of hollow members one movable within the other and means within the said guide for controlling the relative movement of said members. 35

5. An attachment for a power hammer comprising a guide, means for associating said guide with said hammer, said means comprising annular guide rings having 40 flared edges to permit their free movement with respect to said guide.

6. An attachment for a power hammer comprising a guide consisting of a telescoping member, means for securing one end of 45 said member to a boom and a removable nose piece disposed at the opposite end of said guide.

7. An attachment for a power hammer comprising a guide comprising a plurality 50 of nested members, one of said members having a nose piece removably attached to one end thereof.

In testimony whereof I have hereunto set my hand.

TENGEL ANDERSEN.
